STYPTIC PENCIL

Erwin H. R. Lenz, Milwaukee, Wis.

Application May 3, 1937, Serial No. 140,519

8 Claims. (Cl. 128—267)

My invention relates to a new and novel styptic pencil in which the styptic material is molded in the form of cartridges which are expelled or ejected one at a time as required by the user. It is to be understood, however, that the device may be used for other purposes, such as lipstick, or the like.

Obviously styptic material, being soluble in water, decomposes and deteriorates when moisture is applied and the conventional type of styptic pencil when exposed to humidity or moisture soon crumbles and breaks, making a very untidy mass. My device provides a convenient, neat, and practical method of supporting that material during application and provides a protective means of preserving the material and making it possible to carry it on one's person without danger of breakage or deterioration.

The object of my invention is to provide a receptacle that may be filled and refilled with a plurality of reserve cartridges constructed of molded material exposing only one at a time and retaining the extra supply in a sealed container until they are ejected one at a time.

Other and further objects of my invention will become readily apparent to persons skilled in the art from a consideration of the following description when taken in conjunction with the drawing in which

Fig. 1 is a cross sectional view of the assembled device.

Fig. 2 is a perspective view of the outer tubular member shown in Fig. 1.

Fig. 3 is a perspective view of the central tubular member shown in Fig. 1.

Fig. 4 is a perspective view of the inner tubular member shown in Fig. 1.

Fig. 5 is a perspective view of the entire device shown in Fig. 1, in a reloading position and with the protective cap removed.

Fig. 6 is a fragmentary perspective view of the rear end of the central tubular member showing the inwardly projecting member employed.

Figs. 7, 8, and 9 are cross sectional views of various types of cartridges.

Fig. 10 is a plan view of a section of metal which may be employed in the outer tubular member thereby making it possible to eliminate the center tubular member in Fig. 1.

Fig. 11 is a cross sectional view of the outer member with the metal section shown in Fig. 10 attached.

Fig. 12 is a cross sectional view of a modified type of device employing an inner and outer tube.

Fig. 13 is a perspective view of the inner tubu-

lar member illustrated in Fig. 12 showing the cartridges in place.

Fig. 14 is a cross sectional view of still another modified form of device that may be indexed to eject one cartridge at a time.

Fig. 15 is a perspective view of the inner tubular member employed in the device shown in Fig. 14, and

Fig. 16 is a fragmentary perspective view of a cap arrangement for the protection of the cartridges as used in Fig. 14.

Similar characters of reference indicate corresponding parts throughout the several views and referring now to the same the character 10 illustrates a cartridge of styptic material molded in a manner that provides a pointed and a blunt end. In Fig. 1 these cartridges 10 are shown encased in an inner tubular member 11. This tube 11 is provided with a plurality of inwardly projecting members 12 and a longitudinal slot 13 extending from the front of the tubular member 11 to an enlarged opening 14 on the member 11. Prongs 15 on the extreme front end depend inwardly serving the same capacity as the members 12 and an outwardly projecting member 16 engages the slot 13 in the central tubular member 18 as shown. This member 18 has a plurality of inwardly projecting members 19 engaging the longitudinal slot 13 of the member 11. An inwardly projecting member 20 on the extreme rear end of the member 18 also engages the slot 13 of the tubular member 11 when the device is extended in an opened position for loading.

In use the tube 21 encases the members 11 and

18 acting as an enclosure for the entire assembly. 35 In the front end of the tube 21 is a recessed portion 22 for the application of a resilient tube sealing member 23. This member 23 is retained in position by means of an annular band 24 or in any other convenient manner. The depending end of the sealing member 23 extending outwardly from the tubular member 21 securely seals itself around the entire cartridges 10 due to its resilient nature and in doing so it prevents all moisture from entering the inside of the tube assembly thus projecting the reserve cartridges and leaving only the pointed end of one cartridge exposed. As a protection for this exposed cartridge 10 I show a cylindrically shaped cap 25 fastened to the outer tube 21 at 26 by means of a cord or elastic 27. The cap 25 fits snugly over the band 24 as shown and may be applied to the rear end of the device when in use.

The cartridges of molded material may be constructed as shown in Figs. 7, 8, and 9. In Fig. 7

the blunt end of the cartridge is shown having a recess 28 to accommodate the pointed end of the cartridge following in the enclosure as shown in Fig. 1, and in Fig. 9 a band 29 made of a material other than the molded product, is shown in a modified type of cartridge construction. With the band 29 on the cartridge 10 the sealing member 23 closely encircles the band 29 without contacting the molded material thereby permitting the cartridges to slide out freely when forced by the cartridge following.

When molded styptic material is used for constructing cartridges, it may be set into a metallic band or the like by means of a water-proof material.

In operation the device shown in Fig. 1 functions as follows:

When the inner tubular member 11 is drawn out of the central tube 18 the inwardly projecting members 19 retain the cartridges 10 in position and when the tube 11 is again inserted the inwardly projecting prongs 12 will push the cartridges forward thus forcing the exposed cartridge out and replacing it with the succeeding one. The distance that the tube 11 may travel is governed by the projecting member 16 operating in the slot 17 and when the tube 11 is in an extended position out of the center tube 18 additional cartridges may be inserted in the opening 14 of the tube 11.

By employing the extra strip of metal 30 provided with prongs 31 as illustrated in Fig. 10 and adherently attaching it to the inside of the outer tube 21 so that the prongs 31 engage the slot 13 of the tube 11, the center tube 18 may be entirely eliminated. This assembly is illustrated in Fig. 11 on the drawing.

In Fig. 12 is shown an assembly of a modified form of device employing only an inner tubular member 32 and an outer casing 33. The inner member 32 is provided with inwardly projecting prongs 34 at the front end and slots 35 so that one cartridge may be placed into the outer tube 33 and by inserting the inner member 32 the prongs 34 will force the single cartridge 10 through the sealing members 23 held by the band 24 to the outside of the tube 33. The reserve cartridges 10 may be retained in the tube 32 as shown. This form of device necessitates the removal of the entire inner tube 32 every time a new cartridge 10 is placed into the outer tube member 33 and by inserting the member 32 the cartridge 10 is forced to a position where it protrudes ready for use.

Another modified form of device is shown in Fig. 14. This consists of an inner tubular member 36 inserted into an outer tube 37. The tube 37 has an outwardly protruding flange 38 at the forward end and a slideable ring 39 supports a sectional cover 40 and when the ring 39 is slidably forced backward over the outer tube 37 the sections of the cover 40 are caused to spread when they contact the flange 38. This is shown in Fig. 14. The resilient sealing means 23 in this device is shown held in position by an annular groove 41 or in any other convenient manner. The tube 37 is further provided with an inwardly projecting member 42 at its extreme rearward end and this acts as an indexing member and operates in the various grooves 43, 43', 43'' etc., which are positioned in the wall of the inner tubular member 36 as shown in Fig. 15. The device is loaded with reserve cartridges in a manner similar to the one shown in Fig. 1 and by turning the inner tubular member 36 in accordance with graduations 44 on the rearward end of the

device the projecting means 42 enters the various slots 43, 43', etc., thereby allowing the cartridges 10 to be forced out one at a time through the sealing means 23 by means of the pressure exerted by the inwardly projecting prongs 45 on the front end of the tube 36.

Although I have shown and described a particular construction of my device, it is to be understood that I can make such changes as I may deem necessary without departing from the spirit of my invention as set forth in the appended claims.

What I claim and desire to secure by Letters Patent in the United States, is:

1. A device of the character described comprising an inner tubular receptacle closed at one end, said receptacle provided with a plurality of inwardly projecting members, a slot through the wall of said receptacle, said slot of a greater width near the closed end of said receptacle, an outwardly projecting member near the open end of said receptacle, an auxiliary tubular member adapted to telescopically engage said inner receptacle, said auxiliary member provided with a plurality of inwardly projecting members operated in the slot of said inner receptacle and a slot through the wall for engagement with the outwardly projecting member on said inner receptacle, an outer tube adapted to telescopically encase the auxiliary tube, said outer tube equipped with a resilient sealing means at one end, said sealing means supported by said outer tube and having its open end projecting over the end of said outer tube, and cartridges adapted to be inserted into said inner receptacle, said cartridges tapered to a point on their forward end, and propelled by the manipulation of the tubular members so that one cartridge at a time is discharged and one cartridge at a time retained by the resilient sealing means.

2. A device as set forth in claim 1 provided with a cylindrically formed cap closed at one end and designed to fit over the ends of said outer tubular member for the protection of the partially extending cartridge.

3. A device of the character described comprising an inner tubular receptacle having slots in its walls and inwardly projecting members at its open end, an outer tube adapted for telescopically receiving said inner receptacle, said outer tube equipped with a tubular resilient sealing means at one end, said sealing means having its ends projecting over the end of said outer tube, cartridges of molded material adapted to be inserted into said inner receptacle, said cartridges tapered at a point on their forward end, and caused to be discharged through said sealing means on said outer tube one at a time or held in position with one end exposed by means of said resilient sealing means.

4. A device of the character described in combination with a plurality of molded cartridges, tubular members telescopically contacting one another, said tubular members provided with inwardly projecting members, the inner tubular member closed at one end, the outer tubular member provided with a resilient sealing means projecting outward from the end of the said outer tubular member for retaining one of said cartridges in the end of said tubular member thereby sealing the enclosure for the protection of the cartridges encased therein.

5. A device of the character described comprising an inner tubular member closed at one end, an outer tubular member opened at both ends,

said outer tubular member provided with an inwardly projecting member at its rearward end, and a resilient sealing member at its forward end, said inner tubular member provided with inwardly projecting members at its open end, and a plurality of slots in the walls of said inner tubular member, said slots to be equally spaced and of various lengths for the engagement of said inwardly projecting members on the outer tube, graduations indicated on the closed end of said inner tube, said graduations corresponding with the plurality of slots of unequal length, cartridges adapted for engagement into the inner tubular member to be expelled one at a time and retained in a partially ejected position by means of said resilient sealing means on the forward end of said outer tube thereby sealing the reserve cartridges in the inside of said inner tube.

6. A device as described in claim 5 wherein said outer tube is provided with an outwardly extending flange near its forward end, a sectional pro-

20

20

tective cover mounted to an annular band slidably engaging the outer tubular member, the sections of said cover to be provided with a contour that will cause their being separated and spread when said cover is slidably drawn over the flange on said outer tube.

7. A deliquescent stick provided with an enveloping liquid-proof shield with one portion of the stick protruding from the shield, the marginal edge of the shield being resiliently contractable radially about the stick whereby to prevent vapor from entering between the stick and the envelope.

8. A soluble stick provided with an enveloping liquid-proof shield with one portion of the stick protruding from the shield, said shield having a resilient sealing means contractable radially about the stick whereby to prevent vapor from entering between the stick and the shield.
